UNITED STATES PATENT OFFICE

147,994

DESIGN FOR AN EGG COOKING AND SERVING CUP

Joseph L. Siessmayr, New Hyde Park, N. Y.

Application August 26, 1946, Serial No. 132,866

Term of patent 14 years

(Cl. D44—9)

To all whom it may concern:

Be it known that I, Joseph L. Siessmayr, a citizen of the United States, residing at 20 Tuxedo Avenue, New Hyde Park, in the county of Nassau and the State of New York, have invented a new, original, and ornamental Design for Egg Cooking and Serving Cups, of which the following is a specification, reference being had to the accompanying drawing, forming part thereof.

Figures 1 and 2 are a side elevation, and a bottom plan view respectively of an egg cooking and serving cup, showing my new design.

I claim:

The ornamental design for an egg cooking and serving cup, as shown.

JOSEPH L. SIESSMAYR.
